Patented Dec. 5, 1911.

UNITED STATES PATENT OFFICE.

LOUIS A. HENNING, OF TOLEDO, AND WILLIAM B. HENNING, OF NORTH BALTIMORE,
OHIO.

ANCHOR-POST.

1,010,759.

Specification of Letters Patent.

Patented Dec. 5, 1911.

Application filed January 6, 1911. Serial No. 601,202.

To all whom it may concern:

Be it known that we, LOUIS A. HENNING, of Toledo, Lucas county, Ohio, and WILLIAM B. HENNING, of North Baltimore, Wood county, Ohio, citizens of the United States, have invented a certain new and useful Anchor-Post; and we do hereby declare the following to be a full, clear, and exact description of the invention, such as will 5 enable others skilled in the art to which it appertains to make and use the same, reference being had to the accompanying drawings, and to the figures of reference marked thereon, which form a part of this 10 specification.

Our invention relates to anchor posts for fences, and particularly to posts of the character constructed of T-iron and intended more especially for use in wire fence construction, but is not limited to use in such 15 connection.

The object of our invention is the provision of a simple, efficient and strong post of this character, which is composed of few 20 parts, is economical and easy of manufacture, and capable of being easily and quickly set up in properly adjusted position, and which is adapted in numerous ways to obviate the defects, cost and labor 25 30 incident to the construction, setting up and maintenance of other anchor posts.

The invention is fully described in the following specification, and while, in its broader aspect, it is capable of embodiment 35 in numerous forms, a preferred form of the same is illustrated in the accompanying drawings, in which,—

Figure 1 is a side elevation set up of a post and brace embodying the invention. 40 Fig. 2 is a face view of the post plate with which the brace coats. Fig. 3 is a top plan view of the post and brace. Figs. 4 and 5 are top and inner end views of the brace shoe, and Figs. 6 and 7 are top plan 45 and side views on a reduced scale of a post braced for three way fence connections.

Referring to the drawings, 1 designates the post proper of our invention, which is of T-form with its flat or plain face disposed in the direction of greatest pull of an attached fence. A brace-bar 2 also of T-form extends from the post in the direction of strain of an attached fence with its outer end anchored in a suitable manner 50 to the ground at a distance from the post. 55

To obtain the best practical results in strength and convenience of attaching a fence to a post it is found to be important to dispose the plain surface of the post in the direction of pull of an attached fence 60 as above described, and to dispose the flat surface of the brace-bar on the under side thereof with the inner or post end of such flat surface bearing against the flat side of the post adjacent its top whereby contact 65 is effected between the flat surfaces of both the post and brace and a firm and substantial bearing thereby provided.

In order to provide a safe connection between the post and brace at their point of 70 contact, a plate or bracket 3 having spaced arms or webs 4 projecting from the outer side thereof is bolted or otherwise suitably secured to the flat side of the post in position for the plate to preferably receive the 75 thrust of the plain surface of the brace-bar and for the upwardly projecting flange or web 3^a of the bar to fit between the arms or webs 4 of the bracket, as shown. The provision of the bracket 3—4 is not only important in providing a simple and strong connection between the brace-bar and post but also in preventing any twisting or canting of the post, which so frequently occurs with posts upon which wire fences are hung. 80 85 It will be noted that the bracket 4—3 also provides a simple means for securely engaging the brace-bar to the post as the coöperating action of the coacting parts of the bracket and brace-bar eliminates the necessity of 90 using bolts or other means to secure the same together.

To secure a perfect bracing of the post a ground-shoe or pressure-plate 5 is provided and adapted to rest upon the ground 95 or other firm support at a distance from the post and to receive the outward end thrust of the brace-bar. The shoe 5 preferably comprises a base-plate 6, forming a broad bearing surface therefor, and upon the top 100 of this is provided a socket or recess into which the outer end of the brace-bar projects on an incline and bears against the bottom and forward end wall thereof, as indicated. Lips or flanges 7 project inwardly from the forward end portion of the socket walls to engage over the horizontal flanges of the brace-bar to retain the end of such bar properly seated in the shoe. The rear end 8 of the socket rises to meet the 110

under plain surface of the brace-bar and has its side edges provided with upwardly and inwardly extending fingers 9 which engage over the associated edges of the under 5 plain portion of the bar to coöperate with the lips or flanges 7 to hold the brace-bar in engagement with the shoe. The base of the shoe is preferably provided with outwardly projecting flanges or spurs 10 which serve 10 to more firmly anchor it to the subjacent support as is apparent.

The inner end 8 of the ground shoe is provided with a vertical slot 11, Fig. 5, through which one end of a truss-rod 12 projects, while the other end thereof projects through a registering aperture in the plain face of the post 1 flush with one side of the post flange 1^a and thence hooks around said flange as indicated at 13, to anchor it to the post in opposition to its point of attachment to the ground-shoe 5. A nut 14 is threaded on the rod 12 within the socket of the ground shoe, and convenient access is had to such nut by providing openings in the sides of the ground-shoe socket as best indicated in Fig. 1. The purpose of providing a slot 11 in the ground shoe for receiving the truss-rod 12 is to permit of a raising or lowering of such rod as the unevenness of the ground might require. It is apparent that the truss-rod 12 not only provides a rigid connection between the lower portion of the post and the ground shoe to prevent relative outward movements 30 thereof but also serves as a means for straightening the post when set up as a tightening of the nut 14 thereon will effect a movement of the lower end of the post and ground shoe toward each other while 40 the brace-bar prevents a corresponding movement of the shoe and upper end of the post.

To set up an anchor post employing the features of our invention it is only necessary 45 to embed the lower end of the post in the ground in the usual manner and place the outer end of the brace-bar 2 in engagement with the ground shoe 5 and the inner end thereof in contact with the flat side of the post with its flange or web 2^b projecting 50 upwardly between the arms of the bracket 3-4. This being done the truss-rod 12 is engaged to the ground shoe and post in the manner shown and tightened to secure the 55 ground-shoe in proper position to hold the brace-bar in firm contact with the post and to straighten the post as may be desired. It will be noted that the only bolts used are those employed to secure the bracket 3-4 60 to the post, thus making the setting up of the same exceedingly rapid and simple.

It will, of course, be understood that should it be desired to attach one or more lateral fences to the post 1, brackets 3-4 65 may be attached to either or both sides of

the web 1^a thereof, as indicated in Figs. 6 and 7, to receive the upper end thrusts of lateral brace-bars 2 in the same manner as described for the main brace-bar, the outer ends of such brace-bars being mounted in 70 ground-shoes and anchored to the post in the same manner as above described.

We wish it understood that our invention is not limited to any specific construction or arrangement of the parts except in so 75 far as such limitations are specified in the claims.

Having thus described our invention, what we claim as new and desire to secure by Letters Patent, is,—

1. In combination, an anchor post, a bracket secured thereto and having spaced outwardly projecting arms, and a T brace-bar having its flat surface disposed on the under side thereof with the end of such surface in thrust contact with the post and having its upwardly projecting web fitting within the space between the bracket arms, substantially as described.

2. In combination, a post, a T brace-bar therefor having its plain face on the under side thereof, a ground-shoe for receiving the outer end thrust of said bar, said shoe having a cavity in its top over which the bar projects and having portions which contact with the side flanges of the bar to hold it against disengagement therefrom except in one direction, and a truss-rod for adjustably anchoring the ground-shoe to the post, the adjusting means of said rod being located within the ground-shoe.

3. In combination, a post having a flat side, a bracket secured to the flat side of said post and having horizontally spaced arms projecting outwardly from the post with the lower edges of said arms flanged outwardly, a T brace-bar for the post having the post end of its web fitting upwardly between the bracket arms and the associated end of its flat side in contact with the flanged edges of said bracket to resist a relative upward movement of such end of the brace-bar, and means for anchoring the outer end of the brace-bar relative to the post.

4. In combination, a metallic post having laterally projecting flanges, one of which is provided with an aperture, a brace-bar for the post, a ground shoe for receiving the outer end thrust of the brace-bar, and a truss rod having one end adjustably engaged to the ground shoe and its other end projected through said aperture and hooked around a flange of the post which is opposed to the ground shoe.

5. In combination, a T anchor post having an aperture in the flat side thereof adjacent to its ground line, a plurality of brace-bars for the post, ground shoes for receiving the thrusts of the outer ends of

the brace-bars, and truss rods projecting from the ground shoes and having their post ends hooked and engaged around the edge of a flange of the post which is opposed 5 to the attached ground shoe, one of said truss rods projecting through said post aperture and the others lying at the outer side of the flat side of the post.

6. In combination, a T anchor post having an aperture through the flat side thereof 10 adjacent to the ground line, at least two brace-bars extending in different directions from the post, and truss rods adjustably attached at their outer ends to the outer end

portions of said brace-bars and having their 15 inner ends hook shaped and engaging around an opposing flange of the post, one of said truss rods projecting through the post aperture and the other lying at the outer side of the flat side of the post.

20 In testimony whereof, we have hereunto signed our names to this specification in the presence of two subscribing witnesses.

LOUIS A. HENNING.

WILLIAM B. HENNING.
